ALBERT R. SILVER, OF SALEM, OHIO.

Letters Patent No. 105,265, dated July 12, 1870.

IMPROVEMENT IN HUB-BORING MACHINE.

The Schedule referred to in these Letters Patent and making part of the same

To all whom it may concern:

Be it known that I, ALBERT R. SILVER, of Salem, in the county of Columbiana and State of Ohio, have invented a new and improved Hub-boxing Machine; and I do hereby declare that the following is a full, clear, and exact description thereof, reference being had to the accompanying drawing making part of this specification, in which—

Figure 1, plate 1, is a side view of the improved machine, showing a hub confined in place between the chucks, and the mandrel adjusted for boring a taper hole.

Figure 2, plate 1, is a diametrical section through fig. 1.

Figures 3 and 4 are views of the feed-nut and its spherical head.

Figures 5 and 6 are views of the gauge-collars for the mandrel.

Figures 7, 8, 9, and 10, plate 2, are different views of the larger chuck and its attachments.

Figure 11, plate 3, is an inside view of the smaller chuck and its attachments.

Figure 12, plate 3, shows the scale or graduated rule, which is used to adjust the bit on the mandrel, applied to the mandrel, which latter is shown by cross-section.

Similar letters of reference indicate corresponding parts in the several figures.

The object of this invention is to improve that class of hand hub-boring machines, wherein self-centering chucks are employed for centering and gripping the hubs, and supporting and guiding the mandrel which carries the cutting-bits.

To enable others skilled in the art to understand my invention, I will describe its construction and operation.

In the accompanying drawing, figs. 1 and 2, I have represented a hub, A, confined and centered between two chucks, in position for being bored, and, in the same figures the mandrels are represented as adjusted for boring a taper hole centrally through the hub.

The chuck, which is adapted for being applied to the largest end of the hub, consists of three radially movable gripping-jaws a, arranged equidistant apart, and applied, by means of grooved racks a', to the radially-slotted arms D, as clearly shown in figs. 1, 2, 9, and 10.

These slotted arms D are constructed upon the circumference of a ring, D², the cylindrical collar W of which is received into a circular opening made centrally through the circular chuck-plate B, and held in place by means of a ring-cap, k, which is secured to said collar, as shown in figs. 7 and 10.

On the inner side of the chuck-plate B, a scroll-thread, t, is formed, which engages with the teeth on

the grooved racks a' of the gripping-jaws, and moves these jaws either toward or from the center of the chuck-plate, when the latter is turned, and the arms D held stationary, as in the act of confining or releasing a hub.

The sockets or perforated bosses d, on the circumference of the chuck-plate B, are intended for receiving a rod or handle, which serves as a lever, and assists in the adjustment of the gripping-jaws.

G is a circular plate, which is confined in place by means of the cap-ring h, but allowed to turn freely.

This plate G is applied in the center of the chuck-plate B, and constructed with a large opening, O, through it, on one side of its center, through which opening the operator can inspect the work as it progresses.

Another opening, n, of an oblong form, is made centrally through plate G, through which the mandrel E passes, as shown in fig. 2. This oblong opening n allows the mandrel to be adjusted for boring any desired degree of taper.

To the outer surface of the plate G, and secured to it by means of a set-screw, j, and a tongue and groove, is a plate, H, through which the mandrel E passes, and to which this mandrel is connected by means of a feather, v, on the plate H, fitting into a longitudinal groove in the mandrel. The mandrel E is thus allowed free longitudinal and rotary movements, but, in its rotary movements, it carries with it the two plates G and H.

The plate H has an oblong opening through it, through which the set-screw j passes, so that, by loosening this screw, the said plate can be adjusted in a direction with the length of the opening n. This adjustment allows the mandrel to be set for boring any desired degree of taper in hubs, or to be set exactly in the center of the chuck-plate for shouldering the hubs.

It will be seen, by reference to fig. 7, that a scale, S, is marked on the outer face of the rotary plate G, and that a pointer is applied to the edge of the adjustable plate H, so as to point at the marks of the scale. This scale and pointer is designed to afford facility of accurate adjustment of the mandrel for boring taper holes, by indicating at a glance the amount of adjustment of plate H for a given degree of taper.

The chuck, which is adapted for the smaller ends of hubs, consists, mainly, of a circular centrally-perforated plate, C, having a scroll-screw, p, on its inner side, which engages with the teeth on the grooved racks b' of gripping-jaws b.

The racks of the jaws b are applied to and guided by slotted radial arms D¹, arranged at equal distances apart around the circumference of a ring or collar, C', as shown in fig. 11, plate 3.

The cylindrical position of the collar C' is fitted cen-

* Assignor to himself & John Denning of same place.

trally into the chuck-plate C, and connected thereto by the outside cap-ring c, as shown in fig. 2, plate 1.

It will be seen that the two chucks are constructed substantially alike, as far as the gripping and centering features are concerned.

Diametrically across the opening through the collar C is a bar, P, having a depression, s, its center for receiving part of spherical enlargement g', which latter is confined in place in its socket s by means of two half-plates P', that are secured to plate P, as shown in fig. 2.

The ball or enlargement g' is an extension of the dovetail-grooved plate which receives the half-nuts m in a box, F, and this ball, and its attachment to the chuck, is designed to allow the feed-nut to have universal motion, or free oscillation of the machine in boring tapering holes.

The groove i, which is made in the periphery of the ball g', in a direction parallel to the opening through this ball, receives a spring bolt, r, which is applied to the cross-bars P P', as shown in figs. 2 and 11, when it is desired to prevent the feed-nut from turning with the mandrel, but, when it is desired to stop the feed of the mandrel, the bolt r is retracted and held back by turning finger-piece r' against the end of one of the socket pieces P'.

The feed-nut, without the ball-joint, will be found fully described in Letters Patent granted to me, and antedated July 25, 1868, for a hub-boring machine.

The screw-threaded portion of the mandrel E passes through the feed-nut, as shown in fig. 2, and the feed of this mandrel is produced by the threads on the half-nuts m engaging with the mandrel-thread. The half-nuts may be disengaged from the mandrel-thread by giving the cap or box F a half turn.

The stops or gauges f e are adjustable upon the mandrel, and are constructed with gibbs f' e', and set-screws f' e', by which these stops can be secured tightly to the mandrel at any desired point.

Operation.

Having secured the chucks to the ends of a hub, and adjusted the mandrel in the center, run one or more cuts through, as may be necessary, until the hole through the hub is nearly the size of the point end of the "box." Then, with the side of a rule or scale, K, (which is shown in fig. 12, and which will be hereinafter explained,) marked for straight hole, set the bit g to cut the size of the point end of the box, say one-sixteenth scant.

To do this, place the scale S on the enlarged portion of the mandrel E, close to the bit g, on the side next the hub. Set the end of the bit to the figure or mark on the scale indicating the size of the small end of the box, (on the side marked for straight hole.) For example, suppose the point end of the box to be three inches in diameter. Then, set the bit to figure 3 on the scale, and in a corresponding manner for other sizes. Now, run a cut through, draw the mandrel back, and put in a long bit. Set the bit, in the same manner as before, to cut a straight hole the size of the largest portion of the box, (a little full to allow for wedging,) adjust the stop or gauge-plate e to cut the shoulder at the required depth, bore until the said stop or gauge e comes in contact with the plate H on revolving disk G, then release the mandrel from the feed-nut by separating the two halves of this nut. (It will be observed that the feed-nut is made in two sections or halves, which are readily separated or closed on the mandrel by turning the cap or box F to the right or left, as the case may be, so that the mandrel can be run through either way without turning it, thus saving much time.) This stops the feed, when one turn of the mandrel will form a perfectly square shoulder.

This done, and while the long bit is in the mandrel in the center, cut the recess for the washer on the large end of the hub. Now, put in a smaller bit, and set it (using that part of the scale marked for taper hole) to cut the size of the point end of the box; then adjust the mandrel over a little for each cut, and run through as many cuts as may be necessary to make the hole at the shoulder nearly as large as the largest taper portion of the box. Now, before making the last cut, ascertain the exact point on the scale S to which the mandrel must be set to make the last cut the required size to fit the taper of the box. This point is determined as follows:

First, ascertain how much the box tapers to the inch; then find the distance from center to center of the circumference of the scroll-plates, as the machine stands on the hub, (or, from the inside of one to the outside of the other, which is the same.) Now, if the box tapers one-eighth to the inch, which is the usual taper, set the mandrel over one-sixteenth of an inch for every inch of distance between the scroll-plates, as above, and in the same proportion for any other taper. For example, if the box tapers one-sixteenth to the inch, then set the mandrel over one-thirty-second to the inch of distance between the chuck-plates.

Having set the mandrel to the exact point, as indicated by the above rule, run the last cut through; then set the mandrel back to the center, reverse the bit, and set it (by the side of the scale marked for straight hole) to cut the required size for the recess to receive the nut on the end of the axle, with the bit resting against the hub. Set the gauge or stop f back from the cap of the feed-nut the proper distance to cut the recess the required depth. Then, by turning the mandrel to the left, run in until the gauge f comes in contact with the cap of the feed-nut. Free the feed-nut by fastening back the spring bolt r, so that this nut will revolve with the mandrel, when one turn will make a perfectly square shoulder at the bottom of the recess, the whole operation being conducted without removing the machine from the hub.

The rule or scale K, above referred to, is a thin plate of metal, of any suitable length, having one end scored to fit on the enlarged portion of the mandrel, and having marks made on it, properly graduated, for both the straight boring and taper boring. This rule is adjusted upon the mandrel, and against the bit, as shown in fig. 12, and the bit set according to figures marked on the scale, indicating the adjustment sought under this application.

I do not claim the manner of constructing these parts of the chuck-plates which effect the clamping of the hubs and the centering of the same, as these features are shown in patents previously granted. Nor do I claim, under this application, any of the features shown in Letters Patent numbered, respectively, 11,364, 53,216, and 80,837; and, while I prefer to adopt the clamping and centering devices herein described, I do not confine my invention to their use, as other forms of clamps may be employed.

Having described my invention,

What I claim as new, and desire to secure by Letters Patent, is—

1. In combination with a boring-shaft, having a spherical bearing, g', in one of the scroll-chuck-plates, and a sliding bearing in the other scroll-chuck-plate, the detachable cap-ring plate c, ring-collar C', radial forked guide-arms D', and gripping-jaws b b', in the manner shown and described.

2. The ring-collar C', plate P, and removable plates P' P', constructed as described, in combination with the spherical enlargement g' of the nut, all substantially as set forth.

3. The nut F, provided with the spherical enlargement g', substantially as described.

4. The spring bolt *r*, in combination with grooved spherical enlargement *g* on the feed-nut, and a chuck, substantially as described.

5. In combination with the boring-shaft *E*, having a spherical bearing, *g'*, in one of the scroll chuck-plates, and a sliding bearing in the other scroll chuck-plate, the cap-ring *h*, collar *D*, radial forked guide-arms *D*, gripping-jaws *a a'*, and ring-plate *G*, con-

structed with the oblong opening *n*, and scale *S*, slotted and centrally-perforated bearing and indicating-plate *H v*, and screw *j*, all arranged as herein shown and described.

ALBERT R. SILVER.
